UNITED STATES PATENT OFFICE.

CHARLES F. PYM, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF LASTING SHOES.

1,368,969.

Specification of Letters Patent. Patented Feb. 15, 1921.

Original application filed December 13, 1915, Serial No. 66,486. Divided and this application filed May 19, 1917. Serial No. 169,749.

To all whom it may concern:

Be it known that I, CHARLES F. PYM, a subject of the King of Great Britain, residing at Lynn, in the county of Essex and

5 State of Massachusetts, have invented certain Improvements in Methods of Lasting Shoes, of which the following description, in connection with the accompanying drawings, is a specification, like reference characters on the drawings indicating like parts in the several figures.

This invention relates to the manufacture of boots and shoes and more particularly to improvements in methods of shaping or 15 forming the upper materials, this application being a division of application Serial No. 66,486, which was filed on December 13, 1915 and shows one form of apparatus with the aid of which I have successfully practised this invention. While the invention is 20 herein exemplified in its applicability to the shaping or forming of an upper assembled with an insole on a last, and while the invention has important advantages as applied to the lasting of shoe materials thus 25 assembled, it will be recognized that in many of its novel and important aspects the invention is not limited to the particular use illustrated.

30 In accordance with a well-known practice in the manufacture of boots and shoes, after the upper materials have been assembled on the last and pulled over and have been secured upon the last in proper position 35 through assembling tacks at the heel and pulling over tacks at the forepart of the shoe, the margin of the upper is wiped inwardly at the bottom edge of the shoe and hard down over the margin of the sole or 40 sole, hereinafter generically termed for convenience the "sole", and is secured to the sole to hold the upper in lasted position.

At the heel and toe ends of the shoe, the wiping in and laying down of the upper to 45 conform it to the contour of the last and to the edge of the sole is particularly difficult, since there is a fullness in the upper materials at these points which causes the formation of plaits in the materials as they are 50 gathered in over the edge of the sole. These plaits increase the thickness of the upper materials inwardly from the edge of the shoe bottom, and render difficult the closing

over of the wiping means along the plane of the sole with very substantial pressure on 55 the upper materials at the outer edge of the sole.

In order successfully and properly to last the shoe, not only must the marginal portion of the upper materials be tightly gathered in 60 and firmly pressed down over the margin of the sole to form a substantially flat seat upon which to lay the outsole or welt, but in accomplishing this result the upper materials must also be closely and tightly formed 65 to the last and sole at the extreme outer edge of the shoe bottom to present a sharply defined edge line forming one wall of a clear straight crease between the upper and the outsole or welt, usually termed the "welt 70 crease" or "rand crease".

In the practice of the lasting operation prior to my invention, owing to this increased thickness of the upper materials, the upper has been wiped over the outer edge 75 of the shoe bottom with relatively light and ineffective compacting pressure. This practice not only fails adequately to press the marginal portion of the upper down flat over the sole but fails to provide sufficiently 80 hard indrawing frictional pressure against the upper at the edge of the sole closely and tightly to draw and conform the upper to the last and sole at the extreme edge of the bottom of the shoe to provide the requisite 85 sharply defined edge formation previously referred to.

An object of this invention is to obviate such defects in the forming or shaping of upper materials by an improved method. 90 In the attainment of this object, it is proposed by this invention, in one of its aspects, to cause suitable wiping means such as end lasting wipers to embrace the end of a shoe between the exposed face of the sole and the 95 top face of the last and by pressure of the wiper edges against the shoe around its end portion to effect a relative displacement of the shoe and the wipers in a direction transverse to the plane of the shoe bottom to cause 100 the wipers to wipe the upper over the edge of the shoe bottom with effective pressure. The relative displacement effected by wedging action between the wipers and the shoe may take place against relatively heavy 105 yielding resistance effective to cause strong

frictional indrawing pressure by the wipers against the upper materials. This heavy frictional pressure will stretch and tightly draw the upper over the edge of the sole, 5 ironing it down on the edge, and will iron down and crease flat the gathered upper materials inwardly of said edge.

In carrying out the method of this invention, as herein exemplified, the last and shoe 10 are supported with relation to suitable wiping means, such as wiper plates, and the wiper plates are caused to advance and engage the upper below the plane of the shoe bottom and by continued advancing and 15 closing movements are caused to climb or ride up over the edge of the shoe bottom against relatively heavy yielding resistance producing hard frictional indrawing pressure of the wipers against the engaged upper, this resistance and approximately the 20 same pressure against the upper being continued as the wiper plates continue to advance and close inwardly from the edge of the sole.

25 My novel method has the advantage of producing strong indrawing frictional pressure against the upper as the wipers ride up over the extreme edge of the shoe bottom, stretching and tightly conforming the upper 30 along said edge and ironing it down with very substantial pressure to provide a sharply defined edge line formation. The continuation of this pressure as the wipers advance inwardly from the edge of the shoe bottom 35 eliminates the possibility of fullness of the material at said edge due to slack indrawing pressure, and at the toe or heel flattens down and sharply creases the plaits formed by the fullness in the upper material inwardly of 40 said edge as it is gathered in by the wiper plates so that a substantially flat seat is provided.

The resistance producing the hard frictional indrawing and compacting pressure 45 of the wipers against the upper as they are advanced and closed may be provided in any known or suitable manner effective to give the desired result, and the lasting or wiping operation may likewise be effected through 50 any suitable wiping means.

The new method will be more clearly understood from the following detailed description which sets forth how it may be practised with the aid of an apparatus which 55 is illustrated in the accompanying drawings, and the invention will be definitely pointed out in the claims.

In the accompanying drawings, to illustrate the practice of the method of this invention, I have shown the lasting of the heel end of a shoe by lasting instrumentalities of the type shown in said prior application.

Figure 1 of these drawings shows in vertical section the rear part of a last with its

shoe upper and sole supported to receive the action of an illustrated wiper lasting mechanism for wiping the upper materials up and inwardly over the edge of the sole from a point below the plane of the shoe bottom; 70

Fig. 2 is a similar view showing the shoe forcibly engaged below the plane of the shoe bottom by the advancing and closing of the wiper mechanism in the act of wiping the upper upwardly; 75

Fig. 3 illustrates the climbing effect as the wipers are moved upwardly against heavy resistance coincidently with continued advancing and closing movements to cause strong frictional indrawing pressure during 80 the advance of the wipers over the edge of the shoe bottom;

Fig. 4 is a view illustrating the further advance of the wipers over the heel seat with continuing and uninterrupted downward 85 pressure upon the upper.

In practising this invention with the aid of the described apparatus, a last 4 with its shoe upper and sole is mounted on the spindle 2 and clamped thereon by the hold-down 6 with the plane of the shoe bottom determinately above the plane of the retracted wiper plates as suggested in Fig. 1 of the drawings. The wiper head 8 and pivotally connected wiper plates 10 are now projected 90 forwardly and closed inwardly through the action of mechanism including cam 18 and lever 14, 16, as more fully described in said co-pending application, to bring the wipers into heel embracing contact with the 95 upper below the plane of the shoe bottom and it may well be below the plane of the sole on the bottom of the last, the wipers being further supported by links 12 which are substantially parallel to the lever 14. 100 This position of the parts is suggested by the showing in Fig. 2 of the drawings. Contact of the wiper plates with the shoe will occur at about the time that the members 12, 14 reach the position where their pivot 105 points are in vertical alinement, or slightly before the members reach such position, as illustrated in Fig. 2. The wipers are next compelled by further advance of the wiper head, through wedging action caused by the 110 slight incline of the last face at the bottom edge of the shoe and it may be also by the rounded edge formation of the wiping edges, to climb and ride up over the bottom of the shoe. Upward movement of the wipers necessary to enable them to pass over the edge 115 of the shoe bottom is opposed by the coiled spring 26 which encircles the stem 22 of the pivot block 20 for link 12 and is adjustably compressed by nut 24 to act downwardly 120 upon the wiper head with a force causing a strong frictional indrawing pressure of the wipers on the upper, but which permits the wipers to climb up without damaging the shoe stock. This heavy indrawing frictional 125

130

pressure against the engaged face of the upper as the wiper climbs up over the edge of the shoe bottom tightly indraws the upper and irons it down hard at the extreme edge 5 of the shoe bottom. This action is suggested by Fig. 3 of the drawings in which the wiper plates are seen advancing over the edge of the sole with the crimped or plaited edges of the materials forming ahead of them.

10 Heavy downward and frictional closing pressure of the wipers against the thicker upper materials encountered accompanies the further advancing and closing of the wiper plates over the heel seat because of the tension of the coiled spring 26. This downward pressure of the wipers against the plaited edges of the upper is sufficiently powerful to crease and iron these plait 15 down flat as the wipers close over to the limit 20 of their movement, this pressure being approximately the same as that exerted against the upper in climbing over the edge of the sole.

The described apparatus illustrates the 25 manner in which the invention may be practised, but it will be understood that the practice of the invention is not dependent upon the use of the specific apparatus shown. As I am advised, I am the first to form or wipe 30 the upper materials over the edge of the shoe bottom around the end of the shoe by relative movement of the wipers and the shoe effected by wedging action of the lateral periphery of the shoe against the edges of the 35 wipers.

The advantages of this invention are particularly noticeable in lasting the heel and toe ends of welt and McKay shoes and the heel ends of turn shoes. In lasting the heel 40 end of a welt of a McKay shoe, or the "heel seat" as it is commonly termed, and the toe end of a McKay shoe, extremely heavy compacting pressure is necessary in order to flatten out the wiped-over edge of the upper 45 material. This edge of the upper material must be laid down flat in order to form a flat seat for the end of the sole which is laid directly thereon. The edge of the upper, in order to form a flat, firm seat for the sole, 50 must of necessity be stretched and tightly wiped over the bottom edge of the shoe in order to prevent slack. It will be seen, therefore, that the method of the present invention may be practised with particular benefit 55 in connection with end lasting.

The location of the line of initial engagement with the upper relatively to the plane of the bottom face of the last or form may, of course, be varied in accordance with different conditions encountered in operating on different kinds of work. It will also be evident that the invention is applicable to the forming or shaping of assembled upper materials including, for example, the upper 60 leather, the lining and the end stiffener, or 65

to the forming of one or more of such materials, and the term "upper" is accordingly used herein generally as referring to one or more of such materials.

Having thus described my invention, what 70 I claim as new and desire to secure by Letters Patent of the United States is:—

1. That improvement in methods of lasting shoes which consists in engaging the lateral periphery of a shoe continuously 75 around the end of the shoe with the edges of end embracing wipers between the plane of the exposed face of the sole and the top face of the last, and by pressure of the wiper edges against the lateral periphery of the 80 shoe around the end of the shoe effecting a relative displacement of the shoe and the wipers in a direction transverse to the plane of the shoe bottom to cause the wipers to wipe the upper under pressure across the 85 edge face of the sole while maintaining a close conforming relation to the upper around the end of the shoe.

2. That improvement in methods of lasting 90 shoes which consists in relatively and bodily moving and embracing wipers and a last and its shoe in a direction lengthwise of the shoe and in such relation as to cause the wipers to engage the upper around the end of the shoe between the plane of the exposed face of 95 the shoe sole on the last bottom and the top face of the last, and in continuing said relative lengthwise movement with coincident closing movement of the wipers to cause the wipers to be forced to the plane of the ex- 100 posed face of the shoe sole by wedging action of the shoe and with strong frictional indrawing pressure against the upper.

3. That improvement in methods of lasting 105 shoes which consists in engaging the lateral periphery of a shoe continuously around the end of the shoe with the edges of end embracing wipers between the plane of the exposed face of the sole and the top face of the last, effecting a relative displacement of the 110 shoe and the wipers in a direction transverse to the plane of the shoe bottom by wedging action of the shoe against the edges of the lateral periphery of the wipers around the end of the shoe to cause the wipers to wipe the upper across the edge face of the sole 115 while maintaining a close conforming relation to the upper around the end of the shoe, and opposing yielding resistance to such relative displacement of the shoe and the 120 wipers to cause the wipers to press firmly inward against the upper during the wiping operation.

4. That improvement in methods of lasting 125 shoes which consists in effecting relative movement of a last and shoe and end embracing wipers in a direction lengthwise of the shoe and in such relation as to cause the wipers to engage and embrace the shoe end between the plane of the exposed face of the 130

shoe sole on the last bottom and the top face of the last, continuing said relative lengthwise movement and causing said wipers coincidently to move to the plane of the tread face of the sole through wedging action of the shoe against them and then to wipe inwardly over the margin of said sole, and offering yielding resistance to movement of wipers toward the plane of the sole, and continuing said resistance against the wipers as they wipe inwardly over the margin of the sole.

5. That improvement in methods of lasting the heel seats of shoes which consists in effecting relative movement of heel seat lasting wipers and a shoe and its last lengthwise of the shoe and last in such relation as to cause the edges of the wipers to embrace and engage the heel end of the shoe upper between the plane of the exposed face of the sole on the last bottom and the top face of the last, continuing said relative lengthwise movement with a component of relative movement transverse to the plane of the sole effected by wedging action between the shoe and the wipers, and opposing yielding resistance to such relative transverse movement to cause the wipers to operate with strong frictional indrawing pressure against the engaged upper materials.

6. That improvement in methods of lasting the heel seats of shoes which consists in bodily moving heel seat lasting wipers lengthwise of a shoe and its last to engage the edge of the wipers with the heel end of the shoe upper between the plane of the exposed face of the sole on the last bottom and the top face of the last, continuing said bodily lengthwise movement and causing the wipers to move to the plane of the sole by wedging action of the shoe and to advance inwardly over the margin of the exposed face of the sole in continued lengthwise

movement, and offering relatively heavy yielding resistance to movement of the wipers toward the plane of the sole and continuing said resistance after the wipers reach the plane of the sole and advance inwardly over the margin of said exposed face of the sole.

7. That improvement in methods of forming or shaping uppers in the manufacture of boots and shoes which consists in engaging an upper on a substantially continuous line around an end and along the sides of the end portion of a shoe outside of the plane of the shoe bottom, pressing inwardly against the upper along said line with sufficient force to effect a relative displacement of the shoe and said line of pressure in a direction transverse to the plane of the shoe bottom for wiping the upper to the edge of the shoe bottom, and continuing said inwardly directed pressure to gather and wipe the margin of the upper inwardly from said edge and along said plane.

8. That improvement in methods of forming or shaping uppers in the manufacture of boots and shoes which consists in engaging an upper on a shoe form with the edges of end embracing wipers on a substantially continuous line around the periphery of an end of the form, pressing the edges of said wipers inwardly against the upper with sufficient force to effect a relative displacement of the form and the wipers in a direction transverse to the plane of the wipers for wiping the upper to the line where its margin is to be bent inwardly over the bottom face of the form, and continuing said inwardly directed pressure around the end of the form to gather and wipe the margin of the upper inwardly over said face.

In testimony whereof I have signed my name to this specification.

CHARLES F. PYM.

It is hereby certified that in Letters Patent No. 1,368,969, granted February 15, 1921, upon the application of Charles F. Pym, of Lynn, Massachusetts, for an improvement in "Methods of Lasting Shoes," errors appear in the printed specification requiring correction as follows: Page 3, line 40, for the word "of" read *or*; same page, line 113, claim 3, after the word "of," first occurrence, insert the words *the lateral periphery of*; same page and claim, lines 113-114, strike out the words "the lateral periphery of"; and that the said Letters Patent should be read with these corrections therein that the same may conform to the record of the case in the Patent Office.

Signed and sealed this 26th day of April, A. D., 1921.

[SEAL.]

T. E. ROBERTSON,
Commissioner of Patents.
